PAGE 2

Fig. 3.

Fig. 4.

FIG. 5.

Figure 1 is a top perspective view of an airplane in flight showing our new design with the landing gear retracted;

Figure 2 is a side elevational view of the subject airplane depicted in Figure 1 with the landing gear extended;

Figure 3 is a top plan view of the airplane depicted in Figures 1 and 2;

Figure 4 is a front elevational view of the subject airplane showing the landing gear thereof in the extended position; and

Figure 5 is a bottom plan view of the airplane depicted in Figures 1, 2, 3, and 4 with the landing gear retracted.

We claim:
The ornamental design for an airplane, substantially as shown.
